Jacob Himelberger

by his Atty. W. J. Sprague

UNITED STATES PATENT OFFICE.

JACOB HIMELBERGER, OF HOLT, MICHIGAN.

FLOORING-JACK.

SPECIFICATION forming part of Letters Patent No. 285,894, dated October 2, 1883.

Application filed April 3, 1883. (No model.)

To all whom it may concern:

Be it known that I, JACOB HIMELBERGER, of Holt, in the county of Ingham and State of Michigan, have invented new and useful Improvements in Flooring-Jacks; and I do hereby declare that the following is a full, clear, and exact description thereof, reference being had to the accompanying drawings, which form a part of this specification.

10 This invention relates to certain new and useful improvements in the construction of flooring-jacks, and is designed for use in the laying of tight flooring, where close matching or joints are particularly desired.

15 The invention consists in the peculiar construction of a rack-bar, in combination with devices for operating the same, and in the various combination of the parts, all as more fully hereinafter set forth.

20 Figure 1 is a central vertical longitudinal section. Fig. 2 is a top plan view.

In the accompanying drawings, which form a part of this specification, A represents the side walls of my device, which are secured together by suitable girts, *a b*, upon the lower ones of which the rack-bar B slides. In the front ends of these walls A are properly pivoted or journaled the vertical rods C, the lower ends of which have secured to them the wing-dogs D.

25 E represents a lever, the lower end or head of which is bifurcated, and is properly pivoted or fulcrumed upon the center one of the girt-bolts *a*. In this bifurcated head of the lever E is properly pivoted a dog, F, which is designed to engage with the face of the rack-bar B, and behind this lever E are properly hung or pivoted upon one of the bolts *b* the dogs G H, the latter of which is a trifle shorter than the former. A crank-shaft, I, is properly journaled in the side walls at each end

and beneath the dogs G H, by means of which said dogs may be released from their engagement with the rack-bar.

In practice the device is placed over a joist, 45 and the wing-dogs are adjusted to engage with the sides thereof, locking the device firmly to place and forming a resistance against the action of the rack-bar. The end of the rack-bar is then projected against the edge of the board 50 of flooring which it is desired to lay. A forward movement of the lever will cause the dog F to engage with the rack-bar and press such flooring closely to place, the rear dogs engaging with the rack-bar, holding such rack-bar 55 to its position while the lever is retracted for the purpose of exerting a greater strain or pressure upon the board. When this board has been properly nailed, the wing-dogs are released and the device readjusted to the joists, 60 in readiness to be brought into use in laying the next board.

What I claim as my invention is—

1. A flooring-jack consisting of the walls A A, connected together, rack-bar B and lever 65 E, working therein, dog F, pivoted to the lever, dogs G H, connected with the walls, and wing-dogs D, constructed and arranged to engage with a joist when in use, substantially as described.

2. A flooring-jack consisting of the walls A A, connected together, rack-bar B and lever E, working therein, dog F, pivoted to said lever, dogs G H, connected with the walls, the crank-shaft I, for releasing said dogs from their engagement with the rack-bar, and wing-dogs D, constructed and arranged to engage with a joist when in use, substantially as described.

JACOB HIMELBERGER.
